METER BOX LID AND LOCK THEREFOR

Filed May 5, 1930

UNITED STATES PATENT OFFICE

PAUL McAFFEE, OF DALLAS, TEXAS, ASSIGNOR TO DALLAS FOUNDRY, OF DALLAS, TEXAS, A CORPORATION OF TEXAS

METER BOX LID AND LOCK THEREFOR

Application filed May 5, 1930. Serial No. 449,841.

My invention relates to meter box lids and locks therefor and more particularly to meter box lids which have openings for inspection purposes without raising the entire lid; and the object is to provide a meter box lid which is convenient in operation and which can be economically manufactured and which is efficient in use and easily and quickly adjusted to a meter box. Another 10 advantage is that the entire lid need not be removed for the meter reader. In reading meters, the inspector simply uses a key and throws the small supplemental door and reads the meter without removing the main lid. Other objects and advantages will be 15 fully explained in the following description and the invention will be more particularly pointed out in the claims.

Reference is had to the accompanying 20 drawings which form a part of this application.

Fig. 1 is an inverted plan view of the improved meter box lid and the improvements.

Fig. 2 is a side elevation of a key for the 25 lid and lock.

Fig. 3 is an edge view of a lid and a section of the meter rim.

Fig. 4 is a broken inverted view, showing the lid in unlocked position.

Similar characters of reference are used to 30 indicate the same parts throughout the several views.

The drawings show a lid 1 of a meter box. This lid 1 is adapted to rest on the rim 2 of a 35 meter box. The lid 1 has a lug 3 on one edge for catching under the rim 2 of the meter box for locking the lid down on one side of the meter box. A plunger 4 is provided for locking the opposite side of the 40 lid. The plunger 4 is projected under the rim 2 for locking purposes. The plunger 4 is guided by a depending rib 5 through which the plunger 1 moves and the plunger is further guided by a depending lug 6 through 45 which the plunger moves. The plunger 4 is prevented from rocking by a raised rib 7 on which the plunger brushes in its reciprocal motion. The rib 7 is integral with the lid 1. The plunger 4 has a relatively large 50 opening therethrough forming a loop for the

key 8. The key 8 moves the plunger by means of the inner walls of the opening through the plunger. The key 8 unlocks the lid by bearing against the wall 9 and locks the plunger by bearing against the wall 10 when the key is turned. A supplemental locking mechanism is provided for holding the plunger 4 in operative or locked position. The key 8 strikes the pivoted block 11 substantially at the point 12. The block 11 has a stop 13 and a looped spring 14 is fixedly caught in a lug 15 which is integral with the lid 1. The spring 14 holds the stop 13 against a shoulder 16 on the plunger 4. The plunger 4 is held locked until the stop 13 is moved away from shoulder 16 of the plunger. When the key is used to unlock the lid, the key must first push against curved surface 12. This will move the stop 13 away from shoulder 16. On further turning the key 8 will strike the inner wall surface 9 of the plunger loop. This will move the plunger to unlock the lid 1. The plunger 4 will then be brought to the position shown in Fig. 4.

The lid 1 is provided with a door 17 which is hinged to the lid 1. An opening 18 is made in the lid 1 and the door 17 closes the opening. A slotted lug 19 is formed integral with the door 17. The plunger 4 has a lug 20 turned at right angles to the plunger. This lug 20 projects in the slot of lug 19. When the lid 1 is unlocked the door 20 will be brought to the dotted line position shown in Fig. 3 so that the meter can be read without removing the lid 1 from the meter box. The door 20 is thus automatically opened when the lid 1 is unlocked. When the lid 1 is to be locked the key 8 is turned in the opposite direction. The pivoted locking block 12 has been pushed to the position shown in Fig. 4. The key will engage the inner wall 10 and force the plunger to locked position. The spring 14 will cause the stop 13 to snap behind the shoulder 16 and thus lock the plunger 4 in locking position.

What I claim, is,—

1. In a meter box provided with a rim and a cover therefor; said cover having a door opening and a keyhole, a door hingedly con-

- nected to said cover for closing said opening, a slotted lug integral with said cover, a key-operated plunger slidably connected to the under side of said cover and provided with a key loop, and a lug formed on said plunger and projecting into said slotted lug for simultaneously opening said door while said cover is being unlocked and for closing said door while said cover is being locked to said rim.
10. 2. In a meter box provided with a rim and a cover therefor; said cover having a door opening and a keyhole therethrough, a door hingedly connected to said cover for closing said opening, a slotted lug integral with said door, a key-operated plunger slidably connected with the underside of said cover and provided with a key loop, means for automatically locking said plunger in the locked position, and a lug formed on said plunger and projecting into said slotted lug for simultaneously opening said door while said cover is being unlocked and for simultaneously closing said door while said cover is being locked to said rim.
15. 3. In a meter box provided with a rim and a cover therefor; a door hingedly connected to said cover for inspection purposes, said cover having a door opening and a keyhole therethrough and having depending ribs, a key-operated plunger slidably connected with said cover and operating through said ribs and provided with a key loop, means for automatically locking said plunger in the locked position, and means operatively connecting said plunger and said door for simultaneously opening and closing said door with the unlocking and locking movement of said plunger.
20. 40. In testimony whereof, I set my hand, this 28th day of April, 1930.

PAUL McAFFEE.
